UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SAFETY DEVICE FOR PRESSES.

1,257,449.

Specification of Letters Patent. Patented Feb. 26, 1918.

Application filed July 3, 1913. Serial No. 777,873.

To all whom it may concern:

Be it known that I, REUBEN B. BENJAMIN, a citizen of the United States, residing at Chicago, in the county of Cook and State of Illinois, have invented new and useful Improvements in Safety Devices for Presses, of which the following is a full, clear, concise, and exact description, reference being had to the accompanying drawing, forming 10 a part of this specification.

My invention relates to improvements in protective means for punch presses and the like, one of the objects being to provide a barrier to prevent the operator from inserting his hands beneath the operating parts of the press while said parts are moving, this barrier being so constructed that as long as it is raised to permit the insertion of the work in the press the press cannot be 20 tripped, but after the hands of the operator have been withdrawn to a point beyond the barrier and into a zone of safety the barrier may be dropped, permitting the tripping of the press.

For the purpose of disclosing my invention I have illustrated one embodiment thereof in the accompanying drawings. In said drawings—

Figure 1 is a side elevation of a press with my safety device attached;

Fig. 2 is a top plan view of the tripping levers; and,

Fig. 3 is a front elevation of the barrier.

In the embodiment illustrated I have shown a punch press 1, which is of the usual construction and is provided with a spring-returned tripping mechanism 2, the operation of which will trip the press and cause the ram to descend for one punching or cutting operation. This tripping mechanism is operated by means of a lever 3 which is connected thereto by a pair of rods 4 and 5, the rod 4 being connected to a pivoted link member 6 on one side and the rod 5 being connected to said link member on the opposite side.

For protecting the operator's hands and preventing them from being inserted beneath the moving parts of the press while said parts are operating, I provide a barrier 7 which, it will be noted, when in its closed position is immediately above the table 8 of the press. This barrier may be formed in any manner to permit the operator to see therethrough; as, for instance, as shown in

the drawing, it may be slotted, as at 9, or it may be formed of a piece of glass or screen, or, in fact, take any form which while preventing the operator's hands from being placed on the table will permit the operator to see therethrough. The barrier is supported from a rod 10, which extends transversely of the press and is adjustable thereon by means of the slots 11 in the barrier and the locking pins 12 for securing it to the rod. This rod 10 extends from a lever arm 13 pivoted at 14 to the side of the press and connected by a rod 15 with a foot lever 16 arranged in proximity to the foot lever 3. The lever 13 is provided with a stop 17 which, when the lever is operated to raise the barrier 7, is moved into the path of a projection 18 on the link 6 to prevent said link from being depressed. Both the foot levers 3 and 16 are returned to normal position, after having once been operated, by suitable coiled springs 19 and 20.

In operation, the operator first places his foot on the lever 16 which raises the barrier 7 so that the work can be placed in the press. As long as the lever 16 is held down by the foot and the barrier 7 raised the stop 17 will be in the path of the link 6 and the lever 3 cannot be depressed to trip the press. After the work has been properly positioned in the press the operator then withdraws his hands and releases the foot lever 16, placing his foot on the lever 3 to trip the press. The releasing of the lever 16 permits the barrier 7 to drop and the stop 17 to move out of the path of the link 6 so that when the operator presses on the lever 3 the press will be tripped. It will be noted that the stop 17 is in such a position that the barrier 7 must be all the way down so that there is no clearance between the barrier and the table 8 in which the operator could place his hands. It will also be noted that due to the relation of the stop 17 with the link 18, if the barrier is not all the way down to the top of the table the stop will not be in a position to permit the link 18 to move and the press cannot, therefore, be tripped. When the tripping lever 3 is depressed, the projection 18 is moved into the path of movement of the stop 17, so that the barrier 7 cannot be raised as long as the tripping lever 3 is depressed.

In some instances it is desirable to leave a small opening, as at 21, in the barrier

through which work may be fed. It frequently occurs that the press is working on the end of a long length of material, in which instance it would be unnecessary for 5 the operator to place his hands in a dangerous position, so by the provision of the small opening 21 the length of work could be fed beneath the barrier to the press without the necessity of raising the barrier each 10 time to push the work along.

I have shown two operating levers, 3 and 16, in proximity to one another, so that they may be operated by the same foot. It will be understood, however, that this is not essential, as the levers may be placed on opposite sides of the press if desired, and operated by the respective feet of the operator.

Having thus described my invention, what I claim as new and desire to secure 20 by Letters Patent is—

1. In a safety device for presses, the combination with a movable member for tripping the press, of means for operating said member, a movable barrier arranged in 25 front of the operating mechanism of the press and adapted when in closed position to prevent the operator from inserting his hand into the mechanism of the press, means whereby said barrier may be moved 30 to closed position without tripping the press, stop means moved by the raising of said barrier into the path of the operating mechanism of said movable member to prevent the tripping of the press as long as the 35 barrier is in a raised position and stop means controlled by the movement of said operating means for preventing movement of said barrier from said closed position.

2. In a safety device for presses, the combination with a movable member for tripping the press, of a tripping lever for said movable member, means for connecting said movable member with said lever, a pivot arm, a barrier supported on the end of said 45 arm in a position in front of the operating mechanism of the press arranged when in a closed position to prevent the operator from inserting his hand into the operating mechanism of the press, a second lever 50 means connecting said arm with said second lever whereby when the lever is depressed the barrier will be raised, and a stop member on said arm arranged when the barrier is raised to be moved into a position in the 55 path of the connecting means for preventing the operation of said movable member as long as the barrier is raised.

3. In a safety device for presses, the combination with a movable member for tripping the press, of means for controlling said member, a movable guard arranged in front of the operating mechanism of the press and adapted, when in closed position, to prevent the operator from inserting his 60 hands into the mechanism of the press, and

means for holding said guard in closed position controlled by said first controlling means, and means whereby said guard may be moved to closed position without tripping the press.

4. A machine having a part movable in a definite path and having means for controlling the movement of said part, in combination with a movable guard which, in one position, hinders the operator from 75 placing his hands in the path of said part, and means for holding said guard in said position controlled by said first controlling means, and means whereby said guard may be moved to said position without operating 80 said controlling means.

5. A machine having a part movable in a definite path and having means for controlling the movement of said part, in combination with a movable guard which, in 85 one position, hinders the operator from placing his hands in the path of said part, and latch means for holding said guard in said position controlled by said first controlling means, and means whereby said guard may 90 be moved to said position without operating said controlling means.

6. A machine having a part movable in a definite path and having means for controlling the movement of said part, in combination with a movable guard which, in one position, hinders the operator from placing his hands in the path of said part, and movable stop means for holding said 95 guard in said position controlled by said first controlling means, and means whereby said guard may be moved to said position without operating 100 said controlling means.

7. A machine having a part movable in a definite path and having means for controlling the movement of said part, in combination with a movable guard which, in one position, hinders the operator from placing his hands in the path of said part, means for holding said guard in said position, and for controlling the movement of said first controlling means controlled by said first controlling means and by said 110 guard, and means whereby said guard may be moved to said position without operating 115 said first controlling means.

8. A machine having a part movable in a definite path and having means for controlling the movement of said part, in combination with a movable guard which, in one 120 position, hinders the operator from placing his hands in the path of said part, movable stop means for holding said guard in said position and for controlling the movement of said first controlling means controlled by 125 said first controlling means and by said guard, and means whereby said guard may be moved to said position without operating said first controlling means.

9. In a safety device for presses, the com- 130

- bination with a movable member for tripping the press, means for operating said member, a movable guard arranged in front of the operating mechanism of the press and adapted, when in closed position, to prevent the operator from inserting his hands into the mechanism of the press, and means whereby the movement of said operating means to cause the operation of the tripping member locks the guard in closed position, and whereby the movement of said guard to open position locks the operating means in a position to prevent operation of the tripping member, and means whereby said guard may be moved to closed position without tripping the press. 30
- 8
10. In a safety device for presses, the combination with a member for tripping the press movable from the first position in which the press is not operated to a second position in which the press is operated, of a movable guard in front of the operating mechanism of the press and adapted, when in closed position, to prevent the operator from inserting his hands into the mechanism of the press, and interlocking means whereby if said guard is in open position and said tripping member is in said first position, the trip will be locked in this position 35

11. In a safety device for presses, the combination with a member for tripping the press movable from a first position in which the press is not operated to a second position in which the press is operated, of a movable guard in front of the operating mechanism of the press, and adapted, when in closed position, to prevent the operator from inserting his hands into the mechanism of the press, and locking means whereby if said guard is in closed position and said trip member in said second position, said guard will be locked in position, and means whereby said guard may be moved to closed position without tripping the press. 40
